DESIGN FOR A COMBINATION BUMPER GUARD AND LICENSE PLATE HOLDER

Willys P. Wagner, Franklin Village, and Eugene T. Gregorie, Grosse Ile Township, Oakland County, Mich., assignors to Ford Motor Company, Dearborn, Mich., a corporation of Delaware

Application December 6, 1945, Serial No. 124,414

Term of patent 14 years

(Cl. D14—6)

To all whom it may concern:

Be it known that we, Eugene T. Gregorie, of the township of Grosse Ile, Michigan, and Willys P. Wagner, of Franklin Village, Michigan, residing in the counties of Wayne and Oakland, respectively, and State of Michigan, have invented a new, original, and ornamental Design for a Combination Bumper Guard and License Plate Holder, of which the following is a specification, reference being had to the accompanying drawing, forming part thereof, in which:

The characteristic features of the present design are shown by means of full lines in the drawing.

We claim:

The ornamental design for a combination bumper guard and license plate holder, substantially as shown and described.

WILLYS P. WAGNER,
EUGENE T. GREGORIE.
